UNITED STATES PATENT OFFICE.

BIRGER SERLACHIUS, OF JACOBSTAD, FINLAND.

HARROW.

1,084,494.

Specification of Letters Patent. Patented Jan. 13, 1914.

Application filed August 10, 1912, Serial No. 714,406. Renewed October 9, 1913. Serial No. 794,324.

To all whom it may concern:

Be it known that I, BIRGER SERLACHIUS, a subject of the Emperor of Russia, and resident at Jacobstad, Finland, have invented 5 certain new and useful Improvements in Harrows, of which the following is a specification.

The object of the present invention is to provide in a harrow structure a frame of 10 especial design having shafts adjustably mounted thereon, the shafts carrying soil engaging blades. The shafts are arranged preferably 3 in number and are positioned one behind the other. Means is provided for 15 holding the terminal shafts of the series in parallel relation to each other when the said shafts are adjusted at an angle to the line of draft to the harrow and means is provided for moving the intermediate shaft to 20 an angle with relation to the line of draft and at the same time that the terminal shafts are shifted. The angle inclination of the intermediate shaft is equal to the angle of 25 inclination of the terminal shafts, but the connection between the shafts is such that when the ends of the terminal at one side of the harrow frame are moved in one direction the end of the intermediate shaft is moved a corresponding distance in the opposite 30 site direction.

In the accompanying drawing: Figure 1 is a top plan view of the harrow. Fig. 2 is a side elevation of the same.

As illustrated in the accompanying drawing 35 the harrow includes a frame, the side bars of which are made up of a succession of arcuate portions, or sections *c*, these arcuate sections constitute guides for bearings *b*. Collars *e* are carried by the bearings *b* and shafts *a* 40 are journaled at their ends in the collars *e*. Harrow blades *d* are carried by the shafts *a*. A shaft *f* is journaled at the rear portion of the frame of the harrow and a lever *g* is fixed to one end of the said shaft *f*. An 45 arm *k* is fixed to the other end of the shaft *f*. Links *n*, of equal length are located at the opposite sides of the frame of the harrow and the forward ends of the said links are pivotally connected with the forward bearings *b* and the rear ends of the said links 50 are pivotally connected with the rearmost bearings *b*. Thus the terminal shafts and the series of shafts are connected together and are constrained to move in unison along 55 the frame.

A link *m* is pivotally connected at its for-

ward end with an intermediate bearing *b* and at its rear end is pivotally connected to the lower end of the arm *k*. A similar link *m* is pivotally connected at its forward end 60 with the other intermediate bearing *b* and at its rear end is pivotally connected with the lever *g* at a point above the shaft *k*. A link *l* is pivotally connected at its forward end with one of the rearmost bearings *b* and at 65 its rear end is pivotally connected with the upper end of the arm *k*. A similar link *l* is pivotally connected at its forward end with the other rearmost bearing *b* and is pivotally connected at its rear end with the 70 lever *g* at a point below the shaft *f*. By this arrangement it will be seen that when the lever *g* is swung the links *m* will move the intermediate bearings *b* along the intermediate arcuate sections *c* of the sides of the 75 frame of the harrow. But, inasmuch as one of the links *m* is connected with the lower end of the arm *k* at a point below the shaft *f* and the other link *m* is connected at its rear end with the lever *g* at a point above 80 the shaft *f*, the bearings *b* located at the ends of the intermediate shaft *a* move in opposite directions. At the same time that the lever 85 *g* is swung the links *l* move the bearings *b* at the opposite ends of the rearmost shaft 85 *a* in opposite directions, and through the connecting links *n* the bearings *b* at the opposite ends of the foremost shaft *a* are moved correspondingly. By reason of the fact that the link *l* at one side of the frame 90 of the harrow is connected at its rear end with the upper end of the arm *k* and the link *l* at the opposite side is connected at its rear end with the lower end of the lever *g*, these links move in opposite directions 95 as the lever *g* is swung and the links *l* and *m* at the same side of the frame of the harrow move in directions opposite to each other. Therefore when the ends of the terminal shafts at one side of the frame of the 100 harrow move in a forward direction the end of the intermediate shaft *a* at the same side moves in a rear direction and vice-versa. The extent of movement of all of the shafts is practically the same and the shafts approximately are disposed at equal angles to the median longitudinal dimension of the frame of the harrow. By such an arrangement it will be seen that a simple and an effective means is provided for which the 105 disposition of the blades *d* with relation to the line of draft of the harrow and that they 110

may be adjusted while the harrow is in operation also the blades carried by the terminal shafts being disposed opposite to the blades carried by the intermediate shaft. 5 The action of the blades in the soil approximately counteracts each other and thus the tendency to side draft is eliminated.

Having described the invention what is claimed, is:

- 10 1. A harrow provided at its opposite sides with arcuate sections, bearings arranged to move along the sections, shafts journaled in the bearings, links connecting the terminal bearings at the same side of the frame together, means for moving the terminal bearings along the sections on one side in one direction and means for simultaneously moving the intermediate bearings on that side along its section in an opposite direction.
- 15 2. A harrow comprising a frame having at its opposite sides arcuate sections, bearings mounted for movement along the arcuate sections, shafts mounted in the bearings, soil engaging members carried by the shafts, an operating shaft, links connecting the
- 20
- 25

bearings at the opposite ends of the shafts with the operating shaft to simultaneously move the ends of two soil member shafts on one side in one direction and the opposite ends of said two soil member shafts on the other side in the opposite direction, and means for operating the shaft.

3. A harrow comprising a frame having at its opposite sides three arcuate sections, bearings mounted for movement along the arcuate sections, three shafts mounted in the bearings, soil members mounted on the shafts, means for simultaneously moving the ends of the end shafts on one side in one direction and the opposite ends of said end shafts in the opposite direction, and moving the opposite ends of the intermediate shaft in directions opposite to the movement of the respective ends of the end shafts.

In testimony whereof I have hereunto set my hand in presence of two witnesses.

BIRGER SERLACHIUS.
